UNITED STATES PATENT OFFICE.

GEORGE W. BOLL, OF WICHITA, KANSAS.

STACK-COVER.

1,102,466.

Specification of Letters Patent.

Patented July 7, 1914.

Application filed June 1, 1912. Serial No. 701,108.

To all whom it may concern:

Be it known that I, GEORGE W. BOLL, a citizen of the United States, residing at Wichita, in the county of Sedgwick and 5 State of Kansas, have invented certain new and useful Improvements in Stack-Covers; and I do hereby declare the following to be a full, clear, and exact description of the invention, such as will enable others skilled 10 in the art to which it appertains to make and use the same.

This invention is a portable cover for hay, grain, or other products, to protect the same from deterioration due to exposure to 15 rain, snow and the like, the cover being supported by, and conforming to the outline of, the material to be protected.

The invention embodies a sectional metallic cover which may be rolled, or otherwise 20 reduced to a compact space for transportation, which cover may be readily enlarged by the addition of sections thereto.

More specifically stated, the invention 25 comprises a plurality of sections, each section having a series of metallic plates flexibly united, a binding element common to each pair of sections, whereby the various parts may be assembled into a substantially unitary structure, and means for retaining 30 the cover in position.

The invention consists also in the features of construction and combinations of parts hereinafter described and specified in the appended claims.

35 In the accompanying drawings, I have illustrated one embodiment of the invention, but the construction shown therein is to be understood as illustrative, only, and not as defining the limits of the invention.

40 Figure 1 is a perspective view of a cover comprising two sections, illustrating the application of a cover to a stack, and the means of connecting the sections. Fig. 2 is a sectional view on the line 2—2 of Fig. 1. Fig.

45 Fig. 3 is a sectional view through a joint between two cover sections, on the line 3—3 of Fig. 1. Fig. 4 is a detail view showing the interlocking joints of plates composing a section. Fig. 5 is a perspective view of one of the 50 retaining hooks. Fig. 6 is an enlarged detailed view of a hanger for a weight-member.

The structure consists of a plurality of 55 cooperating sections, two of which A, B, are shown in the drawing. Each section com-

prises a series of interior plates 5 and end plates 6. These plates may be constructed of any suitable material, but it is preferred to make them of metal which will withstand the injurious effects due to exposure to the 60 weather. The plates are preferably made of thin or pliable metal, first, to permit the cover as a whole, or in sections, to be rolled into a compact space for storage or transportation, and, second, to adapt the cover 65 as a shelter for material of different outlines, for example, a conical stack or an oblong stack. Each plate 5 is turned upon itself, as at 7, (Figs. 2 and 4) to form an outwardly bent flange along one horizontal side edge of the plate, and is also turned upon itself at 8 to produce an inwardly bent flange along the opposite longitudinal side edge thereof. Each plate 5, therefore, 70 is provided with oppositely bent flanges 7, 75 8, the flange 7 of one plate engaging with the flange 8 of the next adjacent plate to form a weather tight joint, where they may be riveted, as shown in Fig. 2. The end plates 6 are preferably provided with the 80 flange 7 along one side thereof only. The other side of plate 6 is provided with a clip 9 adapted to support a weight member 10, suspended by any suitable means, such as the cable 11. These weight members operate 85 to retain the cover upon the material to be protected, and also to keep the plates 5, 6 under tension, thereby preventing the plates from becoming disengaged at the joints 7, 8. Any number of these interlocking plates 5, 6, may be employed to produce 90 a section of greater or less width. If desired the plates may be united through the flanges 7, 8, by bolts 12, or other suitable fastening means. At each end of plates 5, 95 6, there is provided a bead 13 which may be formed by any suitable means, but in the drawing it is composed of a core member around which the material composing the plate is wrapped, as in Fig. 3. Each plate 100 5, 6, is provided, also, with a plurality of retaining members, in the form of hooks 14. Each hook 14 is preferably a flat piece of metal which is bent upon itself to form the flat hook member and the shank, said shank 105 having any suitable means for attaching the hook to a plate, as at 15. One or more of these hooks are placed near each end of the plate, the closed end, α , of the hooks at one end of the plate 5 or 6 being prefer- 110

ably positioned opposite to the closed end, *a*, of the hooks at the other end of the plate, as illustrated in Fig. 1.

In assembling the parts of the cover, the 5 plates 5 are coupled together until a section of sufficient length is constructed, whereupon the end plates 6, with their attached plates, are coupled to the intermediate plates 5, by means of the interlocking flanges 7, 8. 10 The edges of sections A, B, are brought into engagement, preferably, to permit one section to overlap the other, as in Fig. 3, thereby bringing the hooks 14 of the adjacent sections into register and permitting the 15 bead 13 of one section to abut against the under face of the adjacent section for the purpose of producing a joint which will exclude the access of rain, snow and the like, to the material under the cover. A rod 16 20 (Figs. 1 and 3) is passed into engagement with the oppositely positioned hooks 14 of the adjoining sections A, B, where said rod operates to retain the sections and the various plates 5, 6, composing said sections, 25 into a unitary structure. If desired, the free ends of the hooks 14 may be bent down to prevent the rod 16 from working out of engagement with the hook. It will be observed that the rod 16 and the bead 13 are 30 preferably positioned out of alinement with each other (as shown in Fig. 3) whereby the rod 16 may operate to depress the overlapping end of the section, such as B, to retain the section in firm engagement with the 35 bead 13 for the purpose of producing a firm union therewith. When it is desired to transport the cover, or to store it away, the rod 16 is disengaged from the series of hooks 14, permitting the sections A, B, as

unitary elements, to be rolled into compact 40 form, or these sections A, B, may be divided into smaller parts by disengaging the plates 5, 6, at the joints 7, 8 thereof.

Having thus fully described my invention, what I claim as new, and desire to secure by 45 Letters Patent, is:—

1. In a device of the class described, a plurality of separable sections, each comprising a plurality of plates, a plurality of opposed staggered hooks, a weather bead formed on each of said plates adapted to engage with the under face of an adjacent plate, said bead coöperating with said plate to produce an interiorly disposed and substantially weather tight joint, and a single binding element common to all of said hooks to retain the bead and plate in a firm contact relation. 50

2. In a device of the class described, a plurality of separable sections, each section comprising a plurality of plates, a plurality of opposed staggered hooks, a weather bead formed on each of said plates adapted to engage with the under face of an adjacent plate, said bead coöperating with a plate to produce an interiorly disposed weather tight joint, and to thereby form a chamber between the edges of engaging sections, and a continuous binding element adapted to engage with all of said hooks and to be positioned out of alinement with the weather bead. 65

In testimony whereof, I affix my signature, in presence of two witnesses.

GEORGE W. BOLL.
